CLAIM

The ornamental design of an art materials storage rack, as shown.

DESCRIPTION

FIG. 1 is a perspective view of an art materials storage rack showing our new design.

FIG. 2 is a top plan view thereof.

FIG. 3 is a front view thereof.

FIG. 4 is a left side view thereof.

FIG. 5 is a bottom plan view thereof.

FIG. 6 is a rear view thereof; and,

FIG. 7 is a right side view thereof.
